UNITED STATES PATENT OFFICE.

CARLO DE-FELICE, OF NEW YORK, N. Y.

DENTAL PLATE.

1,298,673.

Specification of Letters Patent.

Patented Apr. 1, 1919.

Application filed December 27, 1915. Serial No. 68,654.

To all whom it may concern:

Be it known that I, CARLO DE-FELICE, a citizen of the United States, and a resident of the borough of Manhattan, in the city, county, and State of New York, have invented new and useful Improvements in Dental Plates, of which the following is a full, clear, and exact description, reference being had to the accompanying drawings, 10 forming a part of this specification.

This invention relates to dental plates, and has for its object to provide a dental plate which is light in weight, sanitary, and simple, and inexpensive to manufacture.

15 Another object is to produce a dental plate as above which will hold securely to the mouth of the user by means of suction resulting from the construction of the same. Other objects and advantages will be apparent to those versed in matters of this kind. Dental plates as a rule are made of rubber composition, and in some instances of metal. It will be understood that this invention will be produced in any suitable material as 20 25 found best adapted to the purpose. To better understand my invention reference should be had to the accompanying drawings in which—

Figure 1 is a perspective view of a dental 30 plate made according to my invention.

Fig. 2 is a top plan view of a slight modification.

Fig. 3 is a plan view of the bridge or spider.

35 Fig. 4 is a cross section of a plate made from metal.

Fig. 5 is a cross section of a plate made of metal and rubber composition.

Fig. 6 is a cross section illustrating an 40 other modification of my invention.

In Fig. 1, 1 is the tooth carrying member, 2 are the teeth, and 3 is a bridge or spider adapted to be carried by member 1, and is so shaped as to fit the roof of the mouth of the 45 wearer.

In the usual practice a dental plate or that part which carries the teeth, consists when finished of a single member. I am aware that in some instances this integral piece has 50 openings cut in it for the purpose of making same lighter and also to facilitate cleaning the same, but the plates are never-the-less produced in one piece. In carrying out my invention, I may employ all metal or all 55 rubber composition or other suitable plastic

material, and during the course of manufacture, I produce a suitable U shaped member 1, and a bridge or spider 3. The U shaped member 1 which is adapted to fit the mouth carries the artificial teeth 2, and secured to 60 this member 1 is the spider 3.

If the tooth carrying portion and the spider is made entirely of metal the two members will be so joined together by soldering, riveting, or in some other suitable 65 manner as to represent a dental plate substantially as shown in Figs. 1 and 2. In Fig. 3, the spider it will be seen, is provided with depressions acting as vacuum cups for the purpose of causing the member 1 to ad- 70 here by suction to the mouth of the wearer.

It will be understood that this spider may be of any suitable shape, may be constructed of metal or other material for composition. It will also be understood that member 1 may 75 be constructed of metal or other suitable material, and for the purpose of more clearly illustrating the various ways in which my invention may be put into practice, I refer to Fig. 4 which is a cross section of Fig. 2 on 80 the line A—B, in which 1 is the tooth holding member, 2 is a tooth secured thereto in any suitable manner.

5 is the point at which 5' of Fig. 3 is joined, and 6 and 6' represent vacuum cups 85 similar to those carried by member 3, but disposed along the upper edge of member 1 substantially as indicated in Fig. 5, which is also a cross section of Fig. 2 on the line A—B, 1 is the tooth carrying member with 90 its suction cups 6 and 6', 2 is the artificial tooth, and 7 represents a suitable plastic composition such as rubber molded around 1 and incasing the upper part of 2. 7' is a similar composition inside the U shaped 95 member 1, so that in this construction most of the member 1 is incased in a composition which may be so colored as to represent the natural gums of the person wearing the dental plate, and at the same time permit member 1 to extend along the upper edge, thus exposing the vacuum cups and not interfering with their function.

Fig. 5 illustrates another modification in 105 which member 1 is entirely made of composition the vacuum depressions being molded right in to the material itself, the said member carrying the artificial tooth 2.

In this construction, if spider 3 is of metal it would be inserted as at 8 into member 1, 110

while the composition is in a plastic or workable state. If, however, said spider is made of similar material to member 1 it will then be attached at 5 in any suitable manner such as for instance by vulcanizing.

I am aware that dental plates having a spider portion provided with openings so as to leave a portion or portions of the roof of the mouth exposed, have been made; but this 10 feature alone is not sufficient to efficiently retain the device in position. I have found that the suction cups provided along the edges of the plate proper, such as indicated at 6 and 6' in the drawings, are most effective 15 in assuring together with the form of spider described, a most firm grip securing the artificial denture in its proper position and this results in great comfort for the wearer being able to retain the device and to use the same 20 with greater ease.

Thus it will be seen that I produce a dental plate which is sanitary and light and which also has the advantage of exerting

great suction owing to the arrangement of the vacuum chambers provided for.

It will be understood that I do not wish to limit myself to the exact details as herein disclosed, it being within the scope of the invention to vary the same in order to best meet the demands in a particular case, or to 30 otherwise modify the same as existing practice in the dental art may dictate.

Having fully described my invention, I claim—

A dental plate comprising a teeth holding 35 portion adapted to be mounted around the gums, suction means around the edges of said teeth holding portion, and a bridge portion comprising a suction cup and arms connecting said suction cup, to said teeth 40 holding portion.

CARLO DE-FELICE.
